UNITED STATES PATENT OFFICE

2,466,132

TWO-CYCLE ENGINE AND COMPRESSOR

Hector Tétreault, Montreal, Quebec, Canada

Application May 27, 1946, Serial No. 672,381

1 Claim. (Cl. 230—56)

1

The present invention pertains to a novel two-cycle engine and compressor, and the principal object is to provide a device of this character in which the cylinders, horizontally aligned, are not rigidly anchored, in order to eliminate undue strains on the structure.

In the accomplishment of this object the aligned cylinders are carried by supports which in turn are slidably mounted on a base. Although the mechanism is for the most part in dynamic balance, any unbalance that occurs is permitted to become converted into a sliding movement of the supports, in the absence of a rigid anchorage. At the ends of the base are provided shock absorbers which are engaged by the supports in the event the supports reach an extreme position.

Between the aligned engine cylinders is mounted a compressor cylinder sealed therefrom. A common piston rod carries a piston in each of the three cylinders, the intermediate piston operating as a compressor inasmuch as its cylinder is provided with fluid inlet and outlet means at opposite sides of the piston.

The engine cylinders are equipped for two-cycle operation in which certain ports are controlled by the piston in the usual manner. The invention is applicable to both steam and internal combustion engines, although the latter is illustrated herein. The internal combustion engine is equipped with electrical ignition means, and in this connection a further object of the invention is to operate the ignition circuit in timed relation by means of the engine pistons.

For this purpose the ignition means for each cylinder is in a circuit with a fixed and a movable contact mounted on the cylinder wall. The movable contact is connected through the cylinder wall to a lever positioned within the cylinder and spaced slightly from the inner cylinder wall. The skirt of the piston is tapered to enter between the lever and the cylinder wall and thus operate the movable contact and close the ignition circuit at the proper time.

The invention is fully disclosed by way of example in the following description and in the accompanying drawings in which:

Figure 1 is a longitudinal section of the device, partly in elevation; and

Figure 2 is a section on the line 2—2 of Figure 1.

Reference to these views will now be made by use of like characters which are employed to designate corresponding parts throughout.

In Figure 1 is shown a horizontal base 1 on which are mounted uprights or shoes 2 which

2

carry the cylinders of the engine, as will presently be shown. The sliding uprights 2 carry opposed cylinders 3 and 4 fastened by bolts 5. The intermediate uprights 2 are extended to form the spaced end walls or bottoms 6 of the cylinders 3, 4 which are spaced apart. Between these is fastened an aligned and intermediate cylinder 7 by means of bolts 8 for a purpose that will presently be described.

- 10 The head of each cylinder is jacketed at 9 and provided with a spark plug 10 in the end. Each cylinder is also formed with a by-pass 11 positioned to lead from one side of the enclosed piston to the other at certain intervals for the usual two-cycle operation. Also, each piston is formed with injection ports 12 and 13 respectively at the head and by-pass for priming. Exhaust pipes 14 lead from the opposite or inner ends adjacent to the walls 6.
- 15 20 A piston rod 15 is mounted axially in the aligned cylinders and is supported in bearings 16 on the end walls 6. Pistons 17 are carried by the ends of the piston rod and work in the respective cylinders 3 and 4. Another exhaust port 18 is formed in each cylinder head and is adapted to be covered at times by the corresponding piston 17 as in the usual two-cycle operation.

25 Each cylinder carries externally a fixed contact 19 and a movable contact 20 controlling the corresponding ignition circuit. Each contact 20 is carried on a stem 21 passing slidably through the cylinder wall and there attached to a spring lever 22. The flared skirt 23 of the cylinder is adapted to wedge between the lever 22 and the inner cylinder wall, thereby closing the ignition circuit at the proper time.

30 35 In the intermediate cylinder 7, the piston rod 15 carries a compressor piston 24. The cylinder 7 has intake and exhaust ports 25 and 26 respectively for air or other fluid. It is thus apparent that the piston 24 within the cylinder 7 operates as a compressor.

40 45 It has been stated that the uprights 2 are freely slidable on the base 1. The pistons and cylinders remain for the most part in dynamic balance without restraint on the uprights 2. However, some shifting might occur, and this is permitted to take place rather than provide rigid anchoring means for the cylinders.

50 55 At each end of the base 1 is provided a shock absorber including a bumper 27 having a stem 28 projecting slidably through a finger 29 on the base. The stem is surrounded by a shock absorbing spring 30 bearing on the head and the finger.

Thus, if either upright approaches an end of the base 1, it is automatically cushioned.

Although a specific embodiment of the invention has been illustrated and described, it will be understood that various alterations in the details of construction may be made without departing from the scope of the invention as indicated by the appended claim.

What I claim as my invention is:

A two-cycle engine and compressor comprising a pair of engine cylinders mounted in horizontal alignment and spaced apart, a compressor cylinder mounted between the engine cylinders, a piston rod slidable axially in the several cylinders, pistons carried by said rod and working in the respective cylinders, intake and exhaust means for the several cylinders, ignition means in the engine cylinders, and fixed and movable contacts on said engine cylinders for

controlling the ignition means, levers in the engine cylinders and connected to said movable contacts, the pistons in the engine cylinders having tapered skirts each adapted to wedge between a lever and the adjacent cylinder wall to actuate said movable contacts.
